(57) **CLAIM**

We claim the ornamental design for a portable welder, as shown.

DESCRIPTION

FIG. 1 is a front, left perspective view of a portable welder embodying our new design.

FIG. 2 is a rear, left perspective view thereof.

FIG. 3 is a left-side elevational view thereof.

FIG. 4 is a right side elevational view thereof.

FIG. 5 is a top plan view thereof.

FIG. 6 is a bottom plan view thereof.

FIG. 7 is a front elevational view thereof; and,

FIG. 8 is a rear elevational view thereof.

The broken line portions of the disclosure are for illustrative purposes only and form no part of the claimed design.
